Patented Jan. 16, 1917.

3 SHEETS—SHEET 3.

UNITED STATES PATENT OFFICE.

WILLIAM COTTRELL, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SAFETY DEVICE FOR PRESSES.

1,212,187.

Specification of Letters Patent. Patented Jan. 16, 1917.

Application filed May 23, 1914. Serial No. 840,456.

To all whom it may concern:

Be it known that I, WILLIAM COTTRELL, a citizen of the United States, residing at Chicago, in the county of Cook and State 5 of Illinois, have invented new and useful Improvements in Safety Devices for Presses, of which the following is a full, clear, concise, and exact description, reference being had to the accompanying drawing, forming 10 a part of this specification.

My invention relates to improvements in safety devices for presses of various characters and particularly for punch presses.

My invention is particularly designed for 15 the protection of an operator working on a stamping press which press uses a stripper plate, one of the objects being to provide means for preventing the operator from getting his hands in a dangerous position 20 during the operation of the press, and for preventing the press from being operated when the stripper plate of the press is raised for the purpose of inspection, changing dies, etc.

25 I have illustrated in the accompanying drawings one embodiment of my invention, in which drawings—

Figure 1 is a side elevation of the right hand side of so much of the press as is necessary to disclose my invention; Fig. 2 is a side elevation of the left hand side of the press; Fig. 3 is a front elevation of the press; and Fig. 4 is a detail showing the tripping and locking mechanism of the 35 press.

Referring to the drawings, the press 1 is of any of the well-known constructions and is provided with the usual trip clutch 2 which is adapted to be operated by a tripping mechanism of any well-known construction. That illustrated in the drawings comprises a bell crank lever pivoted to a bracket 3 and having one arm 4 thereof adapted to lie in the path of the clutch 40 mechanism to hold this mechanism out of tripped position. The opposite arm 5 of the crank lever is connected by a suitable rod 6 with a pivoted arm 7 and held in its raised or non-operative position by a coiled spring 45 8. This arm 7 is also connected by a rod 9 with a suitable foot or hand lever (not shown). In addition to the spring 8 for holding the foot lever raised and the tripping mechanism thus in a non-operated po-

sition, I provide a coiled compression spring 55 10 for holding the bell crank lever or latch above described in a non-operated position. This mechanism above described is of the usual construction, and, in operation, when it is desired to trip the press, pressure is 60 applied to the hand or foot lever thereby throwing the arm 4 out of the path of the projection on the tripping clutch permitting this clutch to operate and thereby causing the punch or ram of the press to descend. 65

The press shown in the accompanying drawings is provided with a stripper plate 11 through which the punch of the press is adapted to operate and beneath which the material is adapted to be fed. This stripper 70 plate extends over the die 12 and is mounted upon the lower ends of a pair of vertical posts 13, one arranged on each side of the press and operating in suitable guides 14 formed in castings 15 bolted or otherwise 75 secured on the stationary frame of the press. Suitable sockets 16 are provided on the stripper plate for the reception of the lower ends of these posts 13 to secure the same to the stripper plate 11. To accommodate dies 80 of various sizes the position of the stripper plate is adjusted by means of pins 17 which engage any one of a plurality of small holes 18 formed in the posts 13, the pins 17 passing through a collar 19, on the posts, which 85 is attached to the raising mechanism as hereinafter described. The stripper plate is adapted to remain in its lowermost position during the operation of the press, and, in order to prevent the operator from getting 90 his fingers in a dangerous position during the reciprocation of the ram or punch of the press, I mount on this stripper plate a guard 20, which extends across the front of the press and around on two sides of the press. 95 This guard being of sufficient height and extending far enough around on each side to completely inclose the movable operating parts of the press so that there will be no danger of the operator inserting his hands 100 in a dangerous position during the movement of the ram of the press.

In the operation of a press of this character it frequently becomes essential that the stripper plate be raised for the purpose of 105 inspecting the dies or inserting new dies and the like. To raise the stripper plate, and, at the same time, prevent the press from be-

ing tripped while the stripper and with it the guard are being raised, I provide a raising and locking mechanism. To the collar 19 on the right hand rod 13 I pivot a link 21, the upper end of which is pivotally connected to the lower end of a second link 22. The upper end of this link 22 is pivoted to the side frame as at 23 and projecting above the pivoted point is a stop portion 24 adapted, 10 when the links are operated, to be thrown into the path of the bell crank lever arm 4. The link 22 is provided at its lower end with a forwardly extending portion 25 to which is secured the handle bar 26. The opposite 15 end of this handle bar is connected to a similarly shaped bell crank lever 27 mounted on the opposite side of the press. This lever is connected by a link similar to the link 21 which, in turn, is connected to the collar 19 20 on the upright 13 on the left hand side of the press. This arrangement provides means whereby when the handle bar is raised, the treadle being first released, as shown in dotted lines in Fig. 1, the stripper plate 11 and 25 with it the guard 20 are raised to permit access to the dies. At the same time that the handle 25 is raised it rocks the link 22 on its pivot, throwing the stop projection 24 in the path of the bell crank arm 4 so that this bell crank arm cannot be moved, thereby 30 preventing the arm from being operated by the foot lever to trip the press.

It sometimes happens that when the tripping mechanism is thrown into an inoperative position to thereby permit the clutch to release so that the press will not operate, the clutch parts stick, and in spite of the fact that the press is supposed to have been disconnected continues to operate. Therefore, 35 in order to prevent accidents of this kind happening when the guard 20 is in a raised position and the operator exposed to danger, I provide means to absolutely lock the press from operating when the guard is raised. At 40 the same time, this means provides a mechanism whereby the guard cannot be raised as long as the ram of the press is on its downward movement. On the left hand side of the press, and on the crank shaft of the ram, 45 I provide a cam wheel 28 provided with a cam face 29 and a stop face 30. This wheel is keyed on the crank shaft of the press ram and the cam face 29 occupies the same relative position as the crank of the crank shaft. 50 Pivotaly mounted on the side of the press is a stop dog 31 which is connected by a link 32 with the arm 27 on the left hand side of the press, so that, when the arm 27 is raised, the stop dog 31 will be thrown into the path 55 of the stop face 30 on the cam member, thereby absolutely preventing the rotation of the crank shaft of the ram. This stop face 30 occupies such position that the ram is just starting on its downward movement when 60 the stop face 30 is in a position to be en-

gaged by the dog 31. If the ram has started on its downward movement the cam face 29 will be in the path of the dog 31 and as this dog is connected to the arm 27, it is apparent that the arm and with it the guard and stripper plate cannot be raised until the cam face has moved past the dog. By the time the cam face has moved past the dog the ram will have started in its upward movement and all danger to the operator will 75 have passed.

It will thus be seen that by the above I provide a means which not only serves to absolutely lock the press against operation when the guard is raised, but also serves to 80 prevent the guard from being raised as long as the ram of the press is moving in a downward or dangerous path.

In order that the stripper plate and guard may be held in a raised position when once 85 raised, the treadle having been first released, so that the operator may have both hands free to attend to the changing of the dies or performing other necessary duties, I provide a catch 33 which is pivoted to one side of 90 the frame and is forced to an engaging position by the spring 34. The notch 35 of this catch is adapted to engage under a laterally extending pin 36 on one of the rods 13 when the rod is raised, and thereby hold the rod 95 and with it the stripper plate in a raised position. As soon as it is desired to start the press again the operator may move the catch out of engagement with the pin by the handle 37, when the stripper plate is lowered to 100 assume its proper operating position, it being, of course, understood that the guard drops with the stripper plate and the operator is thereby prevented from inserting his hands in a dangerous position in the press. 105

While I have shown and described one embodiment of my invention in the accompanying drawings, it will be understood that various modifications and changes may be made therein without departing from the 110 spirit of the invention as set forth in the accompanying claims.

Having thus described my invention what I claim as new and desire to secure by Letters Patent, is:—

1. In a device of the character described, the combination with a tripping mechanism of a press, of a stripper for said press, means for raising said stripper to permit access to the dies of the press, and means operated by said raising means for locking said tripping mechanism against operation as long as the stripper is raised. 120

2. In a device of the character described, the combination with a press, of tripping mechanism therefor, a stripper for said press, a guard carried by said stripper for preventing the operator from getting his hands in a dangerous position as long as said stripper is in operative position, means 125 130

for raising said stripper, and means for locking the tripping mechanism against operation when the stripper is raised.

3. In a device of the character described, the combination with a press, of tripping mechanism for said press, a stripper for said press, means for raising said stripper, and a stop moved in the path of the movable member of the tripping mechanism of the press when said stripper is raised to prevent the press from being tripped as long as the stripper is in a raised position.

4. In a device of the character described, the combination with a press, of a tripping mechanism for said press, a stripper for said press, and an inter-lock between said stripper and tripping mechanism for preventing the tripping of the press when the stripper is moved to an inoperative position.

20 5. In a device of the character described, the combination with a press, of a normally stationary stripper for said press, a tripping mechanism for the press, means for moving said stripper, and means for locking said tripping mechanism against operation when said stripper is moved.

30 6. In a device of the character described, the combination with a press, of a tripping mechanism therefor, a relatively stationary stripping plate through which the movable punch of the press passes in operation, means for raising said plate to permit access to the dies of the press, and means operated by the raising of the plate to prevent the tripping of the press when the plate is raised.

40 7. In a device of the character described, the combination with a press, of a tripping mechanism for said press, a stripper for said press, means for preventing the tripping of the press when the stripper is raised, and means for preventing the raising of said stripper when the ram of the press is moving in its downward path.

50 8. In a device of the character described, the combination with a press, of a stripper therefor, means for raising said stripper to permit access to the dies of the press, and means for locking said stripper in its lowered position as long as the ram of the press is moving in a downward path.

9. In a device of the character described, the combination with a press, of a guard therefor, means for locking the tripping mechanism of the press against operation when said guard is raised, and means for preventing movement of the ram of the press when said guard is raised.

60 10. In a device of the character described, the combination with a press, of a tripping mechanism therefor, a guard for preventing the operator from placing his hands in a dangerous position during the operation of the press, means for locking the tripping

mechanism of the press against operation when said guard is raised, and means for preventing said guard from being raised when the ram of the press is moving in its downward path.

70 11. In a device of the character described, the combination with a press, of a tripping mechanism therefor, a guard for preventing the operator from inserting his hands in a dangerous position during the operation of the press, means for raising said guard to permit access to the dies of the press, means operated by the raising of the guard for preventing the operating of said tripping mechanism when the guard is raised, and means for preventing movement of the ram of the press when said guard is raised.

80 12. In a device of the character described, the combination with a press, of a tripping mechanism therefor, a guard for preventing the operator from inserting his hands in a dangerous position during the operation of the press, means for locking the tripping mechanism against operation when the guard is raised to permit access to the dies of the press, and means for preventing movement of the ram of the press when the guard is raised and for preventing the guard from being raised when the ram of the press is moving in its downward path.

90 13. In a device of the class described, the combination with a press having a ram, and a crank shaft for driving said ram, of a guard, and means exerting force on said crank shaft for preventing movement thereof controlled by said guard.

95 14. In a device of the class described, the combination with a press having a ram, and a crank shaft for driving said ram, of a guard, and means exerting force on said crank shaft for preventing movement thereof controlled by said guard, said means including a stop member secured to said shaft.

100 15. In a device of the class described, the combination with a press having a ram, and a crank shaft for driving said ram, of a guard, means exerting force on said crank shaft for preventing movement thereof controlled by said guard, said means including a stop member secured to said shaft, and a stop member actuated by said guard and movable into the path of said first stop member.

110 16. In a device of the class described, the combination with a press having a ram, and a crank shaft for driving said ram, of a guard and means for holding the guard in guarding position controlled by said crank shaft, and means exerting a force on said crank shaft for preventing movement thereof controlled by said guard.

120 17. In a device of the class described, the combination with a press having a ram, and a crank shaft for driving said ram, of a guard and means for holding the guard in

guarding position controlled by said crank shaft, and means exerting a force on said crank shaft for preventing movement thereof, said last two means including a member secured to said shaft having a cam surface and a stop.

In witness whereof, I have hereunto sub-

scribed my name in the presence of two witnesses.

WILLIAM COTTRELL.
